US00D988083S

(12) United States Design Patent (10) Patent No.: US D988,083 S
Zeng (45) Date of Patent: * Jun. 6, 2023

(54) NAPKIN HOLDER

(71) Applicant: SHENZHEN ZENGSHI VIDEO TECHNOLOGY CO., LTD., Shenzhen (CN)

(72) Inventor: Hongmin Zeng, Shenzhen (CN)

() Term: 15 Years

(21) Appl. No.: 29/782,963

(22) Filed: May 10, 2021

(51) LOC (14) Cl. 07-09

(52) U.S. Cl.

USPC D7/632; D7/631

(58) Field of Classification Search

USPC D7/401.1, 401.2, 500, 505, 600.3, 601, D7/602, 631, 632, 634, 637, 638, 639, D7/640, 641; D6/362, 567, 678.4, 683;

(57) CLAIM

The ornamental design for a napkin holder, as shown and described.

DESCRIPTION

FIG. 1 is a perspective view of a napkin holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the napkin holder that form no part of the claimed design.

1 Claim, 8 Drawing Sheets
